UNITED STATES PATENT OFFICE.

CHRISTIAN J. F. WILFERT, OF DORCHESTER, MASSACHUSETTS, ASSIGNOR OF ONE-HALF TO HIMSELF, AND ONE-HALF TO GEORGE F. WILFERT, OF JAMAICA PLAIN, MASSACHUSETTS.

SOUND-REPRODUCING APPARATUS.

1,308,566.

Specification of Letters Patent.

Patented July 1, 1919.

Application filed June 5, 1918. Serial No. 238,362.

To all whom it may concern:

Be it known that I, CHRISTIAN J. F. WILFERT, a citizen of the United States, residing at Dorchester, county of Suffolk, Commonwealth of Massachusetts, have invented certain new and useful Improvements in Sound-Reproducing Apparatus, of which the following is a specification.

This invention relates to improvements in sound reproducing apparatus, especially phonographs, and has for its chief object to clarify and strengthen the reproduced sound by building up the tones and modifying the tone ratios and by eliminating therefrom the harsh mechanical tones caused by the operation of the apparatus itself.

My invention is based on the relation of elementary tones and of musical notes, which relation has long been a matter of exact knowledge. In brief, I provide a plurality of graduated tone chambers of varying size within a primary tone chamber with which each individual graduated tone chamber independently communicates, whereby the reproduced tones are selectively and sympathetically augmented or reinforced and blended prior to their delivery from the apparatus so that the delivered sound is greatly improved. Further by combining with these graduated tone chambers a duplicate or triplicate horn construction, I am able to further beautify the delivered sound, and by including in the construction a sounding board I further clarify and amplify the tones.

While it has been proposed to strengthen the sound reproduced in such devices, such augmentation has usually resulted in an undesirable distortion of the proportions of the elementary tones in any tone mixture. Furthermore such augmented tones have tended to jumble, especially in the reproduction of articulation.

This I have overcome and avoided by independence of tone augmentations combined with a remixing of such augmented tones.

Other objects and advantages of my invention will appear more particularly hereinafter.

For the purposes of this application, I have illustrated my invention in its application to a phonograph of the built-in or cabinet type, although it will be understood that

its principles are equally applicable to other forms and types of sound reproducing apparatus, and that this selection is purely for illustrative purposes.

The construction and operation of a selected embodiment of my invention which I have found highly satisfactory in use and well adapted to the requirements of manufacture, is described in the following specification, illustrated in the accompanying drawings, and particularly pointed out in the appended claims. Throughout the drawings and specification like reference characters are correspondingly employed, and in the drawings:

Figure 1 is a front elevation of the tone chamber of a machine in accordance with my invention.

Fig. 2 is a front vertical section therethrough.

Figs. 3 and 4 are respectively, a horizontal and a vertical section.

Considering first my tone chamber and amplifier member, I have indicated at 1 spaced vertical walls having top and bottom horizontal closures 2 and vertical end closures 3 from which latter extend forwardly spaced side walls 4 having top and bottom walls 5.

The walls 1, 2 and 3 define a hollow sounding board through which the outwardly flaring sound discharging "horn" or amplifier 6 of the phonograph passes, there being an opening 7 in the upper wall 2, whereby connection with the tone arm may be had.

The walls 3, 4 and 5 with the amplifier 6 define a primary tone chamber 8 extending toward the front wall of the cabinet 12, which wall preferably has an opening therein coextensive with the delivery end of the tone chamber 8. Both the sounding board and amplifier 6 are made of properly resonant stock, as selected fine grain spruce.

As here shown, the amplifier 6 is of plural construction, having individual elements 6, 6¹ and 6² which are graduated in size and therefore respond individually to vibrations of the particular tones to which they are responsive. It is, of course, impossible to avoid sympathetic response, which is characteristic of any amplifier whether of single or plural construction, but the triplicate ar-

angement shown, in which each amplifier is individually available to correct any defective tone unduly magnified by any other amplifier, relieves this defect to a marked extent.

In order, however, to correct any falsity of tone in reproduction, as well as to insure that each tone will receive correct amplification according to its original value in the 10 selection being played, I provide a series of sympathetic resonators, each responsive to vibrate in sympathy with a different tone and each independent of the others so that all possibility of the tones being jumbled is 15 eliminated.

As here shown, these sympathetic resonators may be a plurality of tone chambers of graduated size arranged within the main chamber 8 and individually communicating 20 therewith and with the amplifier. These graduated chambers are indicated by the numerals 9, 10 and 11, and are included within the area defined by the walls 1, 3, 4 and 5, being individually separated from 25 each other by longitudinal partitions 9^a, 10^a and 11^a, inclined partitions, 9^b, 10^b and 11^b, and transverse partitions 9^c, 10^c, and 11^c. Each chamber individually communicates with the amplifier through suitable openings, 9¹, 10¹, and 11¹, and with the main chamber 8 through suitable openings 9², 10² and 11².

The seventh chamber is formed at the base of the vertical section being partitioned off from the rest by the wall 5 through which it is suitably vented as indicated at 17 into the main amplifier.

My tone chamber casing 3 and its amplifier are hung from its projecting top member 2 which rests on the usual shoulder formed along the sides of the phonograph cabinet, thus sustaining these responsive elements free from the rest of the cabinet. The mouth of the amplifier 8 coincides with 45 the usual sound discharge opening at the front of the cabinet.

By making the chambers of graduated capacity, each is individually keyed to vibrate in sympathy with a tone to which no 50 other chamber will accurately respond. This provides against the tones being jumbled as well as insuring that each tone will receive its proper accentuation.

Various modifications in the form and 55 construction of my device may obviously be resorted to if within the limits of the appended claims.

What I therefore claim and desire to secure by Letters Patent is:

60 1. In sound reproducing apparatus, in combination, a conveyer adapted to communicate with a source of reproduced sound and consisting of a plurality of outwardly flaring nested conduits of graduated size and 65 of individually different responsivity, and

a plurality of outwardly directing sympathetic resonators of individually different responsivity arranged in non-communicating relation to each other and independently communicating each with a respective 70 conduit of said conveyer and having individual outlets into a common sound discharge chamber.

2. In a phonograph, in combination, a casing, an amplifier therein adapted to 75 communicate with a source of reproduced sound, a plurality of sympathetic resonators of individually different responsivity arranged within said casing in individually independent non-communicating relation to 80 each other, and comprising partitions forming with the casing walls and amplifier, a series of adjacent chambers of graduated size, each chamber individually communicating with the amplifier, and each having 85 an individual outlet into the casing, said casing constituting a sound discharge chamber common to all of said graduated chambers.

3. In a phonograph, in combination, a 90 casing, an amplifier therein adapted to communicate with a source of reproduced sound, a plurality of sympathetic resonators of individually different responsivity arranged within said casing in individually independent non-communicating relation to each other, and comprising partitions forming with the casing walls and amplifier, a series of adjacent chambers of graduated size, each chamber individually communicating with 100 the amplifier, and each having an individual outlet into the casing, said casing constituting a sound discharge chamber common to all of said graduated chambers, and a sounding board included in said casing and 105 common to all of said graduated chambers.

4. In a phonograph, a walled casing including a sounding board, an amplifier leading through said sounding board into said casing, and having a series of discharge openings in that portion thereof disposed within the sounding board, and a plurality of sympathetic resonators of individually different responsivity arranged in non-communicating relation to each other and independently 110 communicating each with a respective discharge opening of said amplifier, said sounding board common to all of said resonators and forming a part of the walls of each.

5. In a phonograph, a walled casing including a sounding board, an amplifier leading into said casing, a plurality of partitions arranged within said casing and defining with the walls thereof and with the amplifier independent non-communicating tonal chambers of graduated size as to which the sounding board is common, each chamber having an individual inlet opening leading into said amplifier, and said chambers having a common discharge outlet.

125
130

6. In sound reproducing apparatus, in combination, a conveyer adapted to communicate with a source of reproduced sound, a plurality of independent, non-communicating sympathetic resonators of individually different responsivity individually communicating with said conveyer and having individual outlets into a common sound discharge chamber, and a sounding board common to all of said resonators and forming a part of the walls thereof.
7. In sound reproducing apparatus, a walled casing having an amplifier therein adapted to communicate with a source of reproduced sound, and a plurality of partitions arranged on either side of the amplifier and defining with the casing walls tonal chambers independently communicating with the amplifier.
- 10 8. In sound reproducing apparatus, in combination, a conveyer adapted to communicate with a source of reproduced sound and consisting of a plurality of conduits of individually different responsivity, and a plurality of sympathetic resonators of individually different responsivity independently communicating each with a respective conduit of said conveyer and discharging into a common sound discharge chamber.
- 15 9. In sound reproducing apparatus, in combination, a conveyer adapted to communicate with a source of reproduced sound and consisting of a plurality of conduits of individually different responsivity, a plurality of sympathetic resonators of individually different responsivity arranged in non-communicating relation to each other and independently communicating each with a respective conduit of said conveyer, and discharging into a common sound discharge
- 20 chamber, and a sounding board coextensive with all of said resonators.
10. In a phonograph, a walled casing including a sounding board, spaced partitions arranged in said sounding board and defining therewith and with the casing walls, independent tonal chambers coextensive with the sounding board, and an amplifier leading into said casing and having a plurality of openings, each discharging into a respective tonal chamber.
- 15 11. In a phonograph, a walled casing including a sounding board, spaced partitions arranged in said sounding board and defining therewith and with the casing walls independent tonal chambers of graduated size, and an amplifier leading into said casing through said sounding board, and having a plurality of openings in that portion thereof disposed within the sounding board, each 60 opening discharging into a respective tonal chamber.
- 25 12. In a phonograph, a walled casing including a sounding board, an amplifier leading through said sounding board into said 65 casing, and having a series of discharge openings in that portion thereof disposed within the sounding board, and a plurality of sympathetic resonators of individually different responsivity arranged within said 70 casing and independently communicating each with a respective discharge opening of said amplifier.

In testimony whereof I affix my signature in presence of two witnesses.

CHRISTIAN J. F. WILFERT.
